UNITED STATES PATENT OFFICE.

ELIAS S. HALL, OF MILLSTONE, NEW JERSEY.

AEROPLANE.

1,206,435.

Specification of Letters Patent. Patented Nov. 28, 1916.

Application filed September 18, 1914. Serial No. 362,371.

To all whom it may concern:

Be it known that I, ELIAS S. HALL, a citizen of the United States, residing at Millstone, in the county of Somerset and State of New Jersey, have invented certain new and useful Improvements in Aeroplanes, of which the following is a specification.

This invention relates to aeroplanes, and has primarily for its object to devise an efficient means for preserving the equilibrium of the device in various altitudes.

Another object of the invention is to positively preclude possibility of the usual dipping when passing through varying atmospheric zones, at the same time in no way interfering with the operation of the device or retarding its movement.

A further object of the invention is to facilitate the descent by providing an air-resisting foldable crown member which serves in the dual capacity of shifting planes, and being operable at the option of the occupant to regulate the same consistent with the air-pressure so as to coact with the stabilizing means.

A still further object of the invention is to provide, in conjunction with a means for shifting the center of gravity to maintain the equilibrium of the aeroplane, an improved mechanism by which the means for shifting the center of gravity is normally held in close proximity to the bottom of the aeroplane, and is manually releasable by the operator, and is readily retractable to its normal position after the aeroplane has been righted.

Other objects as well as the nature, characteristic features and scope of my invention will be more readily understood from the following description taken in connection with the accompanying drawings and pointed out in the claims forming a part of this specification.

Referring to the drawings: Figure 1 is a top plan view of an aeroplane constructed in accordance with my invention, the foldable crown member being shown in open position. Fig. 2 is a rear elevational view of the device. Fig. 3 is a top plan view showing the foldable crown member in closed position, and disclosing the frame therebeneath. Fig. 4 is a sectional view showing to advantage the manner in which the crown is folded or opened at the option of the operator. Fig. 5 is a detailed enlarged ele-

vational view, partly in section of the mechanism utilized for shifting the center of gravity. Fig. 6 is a sectional view of the same showing to advantage the spring member on the interior of the upper drum, by which the rewinding of the cable on the drum is facilitated. Fig. 7 is a side elevational view of the means for releasing the weight when the center of gravity is to be shifted. Fig. 8 is a sectional view taken through one of the spring drums with which one of the weight-engaging cables is associated; and Fig. 9 is a detailed enlarged fragmentary view of the means for releasing the crown operable wheel.

In the drawings wherein is illustrated the preferred embodiment of this invention, a frame generally designated 5 is provided which in the present instance comprises a pair of longitudinally extending oblong frame members 6 and 7, the former being a skeleton structure and the latter provided with a top and bottom covering 8 and 9. At the jointure of the frame members 6 and 7, a housing for the operator as indicated at 10 is provided which has mounted therein the operator's seat 11 which has in close proximity thereto the mechanism by which the means for shifting the center of gravity and the crown are operated.

The means by which the center of gravity is shifted comprises a housing or frame 12, which has mounted therein in superposed relation a pair of drums 13 and 14, each of which has extended centrally therethrough a shaft 15, one end of the latter being in engagement with a staple 16 which is supported upon a hook 17, the latter being carried by the floor of the frame 5. Each of the drums 13 and 14 is provided with an annular flanges 18 in proximity to their marginal sides so as to provide annular grooves in their peripheries which are adapted for engagement with cables, a cable 19 having one end thereof engaged with the drum 13, while the opposite end thereof passes over a pulley wheel 20 which is journaled in the frame 12, and subsequently passes through the bottom of the frame 12 and is engaged with a weight 21, the latter being in the present instance of a hemispherical configuration as shown to advantage in Fig. 5. A cable 22 has one end thereof engaged in the annular groove on the outer periphery of the drum 14, while the opposite end engages 110

over a pulley wheel 23, the latter being journaled on the interior of the frame 12 in proximity to the bottom thereof, said cable passing through said bottom of the frame 5 and being engaged with the weight 21. Each of the drums has mounted therein a spring 24, one end of each of said springs being engaged with the shaft 15, and the opposite end engaged with the inner periphery of the drum, whereby said springs are tensioned at times for facilitating the raising of the weight 21 after the latter has been lowered for shifting the center of gravity.

A cable 25 has one end thereof fixedly 15 engaged with the center of the weight 21, an intermediate portion thereof being trained over rollers 26 which are journaled on the frame 12, the opposite end of said cable being engaged with a spring drum 27, 20 which is similar in configuration with the drums 13 and 14 and is relatively longer and has engaged with one end thereof a ratchet wheel 28, the drum 27 being normally held in a locked position by a pawl 29 with which is engaged a foot pedal 30, the latter being held upwardly in spaced relation to the floor of the frame adjacent the operator's seat by a coil spring 31 as shown to advantage in Fig. 7.

30 In order to prevent undue lateral displacement of the weight 21 while the aeroplane is in motion, guy ropes 32 are provided, one end of each of which is engaged with the upper face of the weight 21 and the opposite end thereof engaged with a drum 33, each of the latter being journaled on the opposite ends of the frame section 7, and having springs 34 mounted therein so as to normally hold the guy ropes 32 taut.

40 A crown member 35 is carried by the aeroplane frame and comprises a plurality of foldable sections, the sections being made of an impervious material, the margins of each of the sections being engaged with 45 arms. Upon reference to Fig. 3 of the drawings, it is seen that certain of the arms, which have been indicated in the drawings at 36, are stationary, the inner ends thereof being fixedly secured to a hub member 37, 50 while the opposite end of each is engaged with an annular ring 38. The remaining arms as indicated at 36' are movably associated with the hub 37 and ring 38, through the medium of which the crown 35 is folded 55 when desired, said movable arms being arranged in pairs and of a substantially V-shaped configuration, so that each pair of said movable arms are simultaneously operable for either opening or closing the crown member 35. The movable arms are engaged by arcuate securing members 39 through the instrumentality of which the movable arms 36' are permitted to be simultaneously moved.

60 In order to operate the crown member 35, operating cables 40 are provided, one end of each of said cables being in engagement with one pair of movable arms, while the opposite end of each is fixedly engaged with a wheel 41 by which the crown 35 is 70 folded, each of said wheels 41 being normally held in a locked position by a plunger 42, said plunger being engaged with the inner face of the wheel, the latter having a portion thereof formed to provide a ratchet 75 43 in order to insure a positive locking at all times, in view of a spring 44 which is encircled on the shank of the plunger 42 between a pair of guides 45, the upper ends of the latter being formed to provide eyes 80 through which the plunger 42 operates. A releasing pedal 46 is pivotally connected to one of the guides 45, and has the upper end thereof in engagement with the head of the plunger 42 so as to release the same from 85 the wheel 41 as soon as pressure is exerted on the pedal 46, when it is desired to operate the wheel 41 for opening the crown member 35, since the latter is normally held in closed position by elastic strips 47. Brace 90 members 48 are engaged with each of the 95 slideable arms 36' and with a plate 49 which is mounted on a central shaft 50 which extends from the hub member 37.

In operation therefore, assuming that the mechanism for shifting the center of gravity is in its normal position as shown to advantage in Fig. 2 and the crown member 35 is folded as shown to advantage in Fig. 3 and it is desired to operate the aeroplane, the crown member 35 is operated by first releasing the plungers 42 from the wheels 41 so as to permit the actuation of 100 said wheels when pressure is exerted thereon by the operator whom we will assume is in 105 position in the seat 11, pressure on the wheels 41 causing the slideable arms 36' to be operated, thereby expanding the crown member 35, so as to resist the air, the crown member being expanded only a sufficient 110 distance consistent with the air pressure which is required in order to obtain the initial movement of the aeroplane from the earth. When the crown member 35 has been extended to the desired point, pressure is 115 released from the pedal 46, causing the wheels 41 to be automatically locked for holding the crown member 35 in a predetermined position. When traveling in altitudes, should it be desired to operate the 120 weight 21 so as to shift the center of gravity, pressure is exerted on the foot pedal 30, thereby permitting the weight to drop, since the weight is sufficient to overcome the 125 resistance of the springs in the drums 13, 14, 27 and 33, at the same time permitting the weight 21 to be moved laterally automatically according to the direction in which the aeroplane is being displaced. After the 130 aeroplane has been righted, and it is desired

to elevate the weight 21, pressure is exerted on the drum 27 to rotate the same, thereby elevating the weight 21, which is facilitated in view of the fact that while the weight 5 is in a lowered position, the springs in the drums above referred to are under tension, and since the weight is made to be sufficient merely to overcome the resistance of the springs, it is seen that very little pressure on 10 the drum 27 will be required.

It will be understood that the above description and accompanying drawings comprehend only the general and preferred embodiment of my invention and that various 15 minor changes in details of construction, proportion and arrangement of parts may be made within the scope of the appended claims and without sacrificing any of the advantages of my invention.

Having thus fully described my invention, what I claim as new and desire to secure by Letters Patent is:

1. An aeroplane including a frame, a foldable crown structure associated with said frame, elastic elements for normally holding said structure in a folded position, operating cables extending from said structure and operable by the occupant of the aeroplane for opening said structure, and means carried in said frame and in connection with said cables to hold the same in a predetermined position whereby the crown structure is held in a predetermined adjusted position.

2. An aeroplane including a frame, a circular impact member mounted on the top of the frame and being relatively flat to occupy a minimum amount of space, said member being movable in segments, to increase the 35 atmospheric resistance at any part of the frame, and circular securing members en-

gaged with movable portions of adjacent segments to simultaneously move the latter.

3. An aeroplane including a frame, a crown structure associated with said frame 45 comprising a plurality of sections which are independently actuatable, means carried by said frame for actuating said sections independently of each other, means mounted in said frame for locking said sections in a predetermined open position, means for normally holding said sections in a folded position, and means carried by said frame for coöperation with said crown sections to preserve the equilibrium of said frame in altitudes.

4. An aeroplane including a frame, an air resisting crown superimposed on the frame and foldable thereon to decrease the air resistance, and to occupy a minimum 60 amount of space when not in use, said crown comprising a plurality of independently operable sections, whereby any one of said sections may be operatively positioned for atmospherical impact at a predetermined 65 point.

5. An aeroplane including a frame, a foldable crown superposed on the frame, said crown being relatively flat to provide a substantially air-impinging surface remote from 70 said frame, said crown being of a circular contour to permit construction of the same in segmental sections, whereby any section of the crown may be operatively positioned at the desired angle on the frame.

In testimony whereof I affix my signature in presence of two witnesses.

ELIAS S. HALL.
